MATERNITY GIRDLE AND ABDOMINAL SUPPORT

Lillie Marsden Marshall, Washington, D. C.

Application May 17, 1940, Serial No. 335,686

2 Claims. (Cl. 2—41)

The present invention relates to maternity or abdominal girdles or supports.

One object of the invention is the provision of an abdominal belt or girdle intended primarily to be worn by expectant mothers and of such construction as to provide a mild uplift effect on the wearer's abdomen.

A feature of the present invention and another object thereof is the provision in a belt or girdle of the designated class of a front panel composed of soft material and free from bones and stays, said panel being fashioned to provide a concavity on the inner surface thereof conforming approximately to the curvature of the abdomen of the wearer, together with side and rear belt members or portions associated with said panel in such manner as to exert tension on said panel laterally and upwardly of the wearer.

A further object of the invention is the provision of the girdle of the character hereinbefore described and readily capable of being associated if desired with a rear panel adapted to compress and confine posterior portions of the wearer's body.

The above objects of the invention and other objects not specifically referred to but hereinafter appearing are accomplished in the belts or girdles hereinafter described with reference to the accompanying drawing.

In the drawing:

Fig. 1 is a front view of a maternity girdle or abdominal belt or support embodying the present invention;

Fig. 2 is a rear view of the belt or girdle illustrated in Fig. 1;

Fig. 3 is a sectional view on the line 3—3 of Fig. 1;

Fig. 4 is a view similar to Fig. 1 showing another form of the invention.

Referring now to the drawing in detail and first to the form of the invention illustrated in Figs. 1 to 3, the abdominal belt or girdle 10 embodying the present invention comprises, as here shown, a front panel 12 which is composed of soft fabric and which is fashioned to provide a concavity on the inner surface of the panel conforming approximately to the curvature of the abdomen of the wearer both laterally and longitudinally of the latter. Panel 12 is continuous from end to end and comprises an outer layer 14 of inextensible fabric such as silk or any other suitable material and an inner layer 15 coextensive with outer layer 14 and composed of soft fabric such as, for example, flannel. For fashioning panel 12 with the concavity as referred to above, outer

layer 14 is composed of laterally extending sections 16, 18 and 20, the opposite side edges of section 18 being convex and stitched to the adjacent convex edges of panel sections 16 and 20 by lines of stitching 22 and 24, respectively. The inner layer 15 of the panel is similarly formed of sections 26, 28 and 30, intermediate section 28 having convex side edges secured to the adjacent convex side edges of sections 26 and 30, respectively, by seams 32 and 34, respectively. As the sections of both layers of the panel are wider in the central portions thereof than at the ends thereof and as the edges which are stitched together are convex the panel is thus fashioned with a concavity on its inner surface designed to conform as hereinbefore stated approximately to the curvature of the wearer's abdomen. The edges of panel 14 at the opposite ends thereof are inclined toward each other in an upward direction and at said edges the panel is provided with end sections 36 and 38 provided with lacing eyelets 40. Also, a stiffening bone or stay 42 is disposed in each of sections 36 and 38 adjacent the companion row of eyelets 40.

Side and rear members 44 and 46 are attached at the opposite ends, respectively, of panel 12 and as clearly shown in the drawing (Figs. 1 and 2) extend laterally and upwardly of said panel. Said side and rear members 44 and 46 comprise portions 48 of elastic material such as elastic webbing which is preferably elastic in a direction laterally or circumferentially of the wearer and inelastic in a longitudinal direction. The end sections 50 of inextensible material are stitched to the inner edges of elastic portions 48 and are provided with eyelets 52 for the lacing whereby said side and rear members are adjustably attached in respect to panel 12. Also, sections 50 are preferably each provided with a stiffening bone or stay 54. The outer portions 56 and 58 of members 44 and 46, respectively, are formed of inextensible fabric and are stitched to companion elastic portions 48, and the outer edges of sections 56 and 58 are provided with separable fastener members here shown as hooks 60 on section 56 and eyes 62 on section 58. Also, said sections 56 and 58 are each preferably provided with stiffening bones or stays 64.

Flaps 66 are stitched to panel 12 and more particularly to the end sections 36 and 38 of the latter on the inner surface of the panel in position to overly the adjacent sections of said panel and said side and rear members 44 and 46, respectively. As here shown, the belt or girdle 10 is provided with garter tabs 68 and 70 secured

to the lower edge portions of panel 12 and side members 44 and 46, respectively.

It will be observed that the edges of members 44 and 46 at their ends adjacent the upwardly inclined edges of panel 12 are also upwardly inclined toward each other and that the tension exerted by members 44 and 46, when fastened together at the back of the wearer, is directed upwardly and laterally of panel 12. The belt or girdle is thus constructed so that the front panel 12 thereof is tensioned in such manner as to provide a mild and beneficial uplift effect on the wearer's abdomen. As members 44 and 46 are adjustably attached to the lacing as shown and above described, the girth of the girdle can be increased, as desired, without increasing the tension on panel 12 or the pressure thereof on the wearer's abdomen.

In the form of the invention illustrated in Fig. 4 the girdle or abdominal support 10a is provided with a panel 12a of the same construction as the panel 12 of girdle 10 but as here shown the rear portion of the girdle comprises a rear panel 72 of any suitable fabric, which may be elastic as desired laterally or longitudinally or both or inelastic, if preferred. Said panel is adapted to overly and confine the posterior parts of the wearer. Rear panel 72 is preferably longer than front panel 12a but has end portions 74 of substantially the same length as end sections 36 and 38 of panel 12a and are provided with eyelets for adjustably lacing end sections 74 of panel 72 to said end sections of panel 12a. The rear and side members 44a and 46a are of the same construction as the members 44 and 46 of girdle 10 and when the girdle is on the wearer are attached at the edges at the opposite ends of the panel but instead of being attached directly to sections 36 and 38, respectively, of panel 12a are fastened to sections 74 of rear panel 72 preferably by being stitched thereto. Rear and side members 44a and 46a coact with panel 12a in substantially the same way as members 44 and 46 of panel 12, that is, said members when fastened together at the back of the wearer exert a tension on panel 12a laterally and upwardly of the wearer to provide a mild uplift effect on the wearer's abdomen. As shown, panel 10a is provided with garter tabs 76 secured to panel 12a and with garter tabs 78 secured to rear panel 72.

While I have shown and described the preferred embodiment of my invention, it will be understood that the latter may be embodied

otherwise than as here shown and that in the illustrated forms, certain changes in the details of construction and in the arrangement of parts may be made. Therefore, I do not wish to be limited to the invention as herein shown or described except to the extent which may be required by the scope of the appended claims.

Having thus described my invention, what I claim and desire to secure by Letters Patent is:

10. 1. An abdominal belt or girdle comprising a front panel having a plurality of sections arranged to extend laterally of the wearer, each of said sections extending continuously from one end of the panel to the other, and having convex side edges, said sections being stitched together at their adjacent side edges and fashioned to provide a concavity on the inner surface of the panel conforming approximately to the curvature of the abdomen of the wearer, the edges 20 of said panel at the opposite ends thereof inclining towards each other upwardly of the panel, and rear members having side edges at their ends adjustably laced to said edges, respectively, of the panel in substantially parallel relation with the panel edges, and means for releasably securing the other ends of said members to each other under tension thereby to tension the front panel on the wearer to provide a mild uplift effect on the wearer's abdomen, said side and rear members being substantially as wide as said panel at said ends of the panel.

2. An abdominal belt or girdle comprising a front panel having a plurality of sections arranged to extend laterally of the wearer, each 35 of said sections extending continuously from one end of the panel to the other, and having convex side edges, said sections being stitched together at their adjacent side edges and fashioned to provide a concavity on the inner surface of the panel conforming approximately to the curvature of the abdomen of the wearer, the edges of said panel at the opposite ends thereof inclining toward each other upwardly of the panel, side and rear members having edges adjustably laced at their ends to said edges, respectively, of the panel in substantially parallel relation with the panel edges, said side and rear members being elastic in a direction laterally of the wearer, and means for releasably securing the other ends of said members to each other under tension thereby to tension the front panel on the wearer to provide a mild uplift effect on the wearer's abdomen.

LILLIE MARSIDEN MARSHALL.
